(57) **CLAIM**

We claim the ornamental design for a plush toy bus hand puppet, as shown and described.

DESCRIPTION

FIG. 1 is a perspective view of a plush toy bus hand puppet according to the new design.

FIG. 2 is a side view of the plush toy bus hand puppet shown in FIG. 1.

FIG. 3 is the opposite side view of the plush toy bus hand puppet shown in FIG. 2.

FIG. 4 is a top view of the plush toy bus hand puppet shown in FIG. 1.

FIG. 5 is a bottom view of the plush toy bus puppet shown in FIG. 1.

FIG. 6 is a front view of the plush toy bus hand puppet shown in FIG. 1; and,

FIG. 7 is a back view of the plush toy bus hand puppet shown in FIG. 1.

Features shown in broken lines in the drawings are not part of the claim.
